CONTINUOUS SWAGING MACHINE

Warren S. Reynolds, Westport, and John R. Turner, Stratford, Conn., assignors to Remington Arms Company, Inc., Bridgeport, Conn., a corporation of Delaware

Application February 21, 1948, Serial No. 10,104

18 Claims. (Cl. 78—96)

1

This invention relates to swaging apparatus, and contemplates certain improvements in the handling of metal slugs to be swaged and in operating devices for swaging tools.

The invention will be described as applied to the bullet swaging unit of a continuously operating cartridge loading machine. The general arrangement of such machine is shown in the patent to Johnson, No. 2,403,286, July 2, 1946. It comprises a plurality of separate turret stations connected by a conveyor chain which serves both to drive the several turrets and to transfer components being operated upon from one turret to another.

In the bullet swaging unit, to be herein described, lead slugs are fed from a stationary hopper to swaging tools carried upon a continuously revolving turret. After swaging, the formed bullets are transferred to suitable holders on a conveyor chain which engages a sprocket secured to the turret, and are removed from the chain in another unit which is not part of the present invention. The turret may either drive or be driven by the conveyor chain.

In the drawings :

Fig. 1 is a fragmentary sectional elevation of the upper or hopper portion of the machine, showing the slug-aligning and upper swaging punch driving and controlling devices.

Fig. 2 is a fragmentary sectional elevation of an intermediate portion of the machine, showing the slug transfer and swaging tools.

Fig. 3 is a fragmentary sectional elevation substantially on the line 3—3 of Fig. 1, showing a detail of the upper swaging tool operating devices.

Fig. 4 is a fragmentary horizontal section substantially on the line 4—4 of Fig. 1, showing the escapement devices for delivering slugs one at a time.

Fig. 5 is a fragmentary sectional elevation showing a second position of the escapement devices.

Fig. 6 is a fragmentary horizontal section substantially on the line 6—6 of Fig. 2, showing the details of the means for transferring slugs into alignment with the swaging tools; certain parts have been omitted, for greater clearness.

Fig. 7 is a detailed sectional elevation showing the relationship of the swaging tools to the work-piece holders on the conveyor chain.

Fig. 8 is a fragmentary plan view of a portion of a conveyor chain, showing one form of work-piece holding device.

Fig. 9 is a view similar to Fig. 8, showing a modified form of work holding device.

2

The stationary frame of the machine comprises a base portion 10 having upstanding therefrom a generally cylindrical hollow boss 11 which partially supports the revolving turret. Associated with the base 10 are a plurality of vertically disposed columns or posts 12 which form supports for a stationary hopper, identified generally by the numeral 13, and associated parts. The hopper comprises a central conical portion 14 and an outwardly flaring portion 15 connected to the central cone by appropriate webs 16. The junction of the surfaces 14 and 15 is an annular open slot. The lower central portion of the hopper is extended downwardly to form a generally cylindrical boss 17, the axis of which is inclined to the vertical. To the exterior inclined cylindrical surface of boss 17 is secured, by suitable means, the supporting ring 18 of a roller bearing. Said central lower portion of the hopper is further extended downwardly in a cylindrical member 19 which is concentric with the axis of the revolving turret and has integral therewith or rigidly secured thereto the cylindrical cam 20.

The revolving turret comprises a vertically and centrally disposed post or spindle 21 having bearing supports at 22 in the fixed base 10 and its boss 11, and a similar support 23 in the vertically disposed cylindrical boss 19. To the spindle 21 are secured various members which constitute supports for the working parts of the turret. One such support is the frame 24 which comprises a plate 25 apertured to form bearings for a plurality of thrust rods or tool holders 26 which are symmetrically disposed about the entire periphery of the turret. As shown in Fig. 3, the tool holding rods 26 are arranged in pairs, the upper ends of each pair being secured in a block 27 which carries a cam following roller 28 adapted for upward displacement by the upwardly facing cam surface 29 of cam 20. It will be obvious that the tool holders can be arranged for common actuation in groups of any desired number.

The downward or working stroke of each pair of tool holders 26 is effected by the following means:

Each connecting block 27 comprises an upwardly facing substantially hemispherical recess 30 which receives a bearing ball 31. A cam plate 32 is mounted through roller bearings 33 on the fixed inclined boss 17, and thus revolves in an inclined plane. The upper and outer portion of cam plate 32 comprises supports for rollers 34 which engage a hardened bearing ring 35 secured in a downwardly facing but inclined part 55 of the fixed hopper 13. The working face of

bearing ring 35 is at 90° to the bearing supporting face of the boss 17. The lower face of plate 32 comprises recesses 36 which receive the upper portions of the thrust transmitting balls 31. Due to the inclination of cam plate 32, as described, in the revolution of the turret, each tool holding block 27 is in turn moved downward to the position illustrated in the left portion of Fig. 1, and thereafter permitted to be moved upwardly to the position illustrated in the right portion of Fig. 1, said upward movement being effected by cam 29.

The tools carried at the lower ends of the tool holders 26 operate on slugs which are delivered one at a time from the hopper 13 to transfer devices to be described. For so removing slugs from hopper 13, the annular gap at the bottom of the trough formed by hopper surfaces 14 and 15, respectively, is closed by an annular member 37 associated and revolving with the turret. Said member 37 comprises a plurality of tubular passages 38 corresponding in number and associated with the tool holders 26. The upper ends of passages 38 are circumferentially enlarged in a manner familiar in the art to facilitate the entrance of slugs from the hopper into such passages. The slugs are rough cast or cut pieces of the general configuration of a cylinder with hemispherical ends, and it is desirable that they be delivered to the transfer devices one at a time. For this purpose, suitable escapement mechanism may be applied to the lower end of each passage 38. As shown in Figs. 1, 4 and 5, a ring bracket 40 secured to the turret carries on pivot studs 41 a series of pairs of escapement pawls, one pair for each passage 38. Each upper pawl 42 carries on a stud 43 a cam following roller 45 which is urged by a spring 46 into engagement with the surface of a cam ring 47 supported on the main columns 12. Each lower pawl 48 is similarly pivoted and carries a cam following roller 49 urged by a similar spring into contact with surface 50 on said cam ring 47. Each of the pawls comprises a nose portion arranged to extend into a tubular passage 51 through bracket 40, which passage is aligned with passage 38. One position of the pawls is illustrated in Fig. 1, and the reverse position is shown in Fig. 5. It will be obvious that, by appropriate design of the cam surfaces 47 and 50, the pawls may be shifted to deliver individual slugs, while retaining a column of slugs in passage 38, in any desired timed relation to the operation of other parts of the machine. The slugs thus individually released from the passages 38 and 51 are received in a delivery tube 52, from which they are conducted to the transfer devices.

At their lower ends, tool holders 26 receive swaging punches 53 which reciprocate through bushings 54 in a sprocket wheel 55 secured to the turret. Said punches are in vertical alignment with the apertures of swaging dies 56 held beneath the sprocket wheel and spaced therefrom in a member likewise secured to the turret. A swaging stem 57 extends upwardly through the die aperture, being carried in a holder 58 which is reciprocated in proper timed relation to the movement of the swaging punch. Holders 58 are preferably arranged in pairs, like holders 26, the members of each pair being received in a cross-head 59 which carries a cam following roller 60 arranged to be vertically reciprocated by a cam 61 secured to the fixed boss 11. Preferably, the lower end of each swaging stem holder 58 bottoms upon an adjustable set screw 62 during the actual swaging operation.

The slug delivering tubes 52 terminate in bushings 63 carried in apertures in sprocket wheel 55, which apertures are radially inward from the swaging punches 53. Each slug in turn drops through bushing 63 and into the fingers of a transfer device, best illustrated in Figs. 1 and 6. Said transfer devices are preferably arranged in pairs or groups of any desired number, each group having one operator. The device illustrated comprises a radially disposed and forked bar 64 having at its inner end a depending portion 65 which carries a cam roller 66 controlled by a cam track 67 secured to the fixed boss 11. The outer forked end of member 64 comprises a shelf 68 upon which are pivoted the gripping transfer fingers 69, which fingers are urged apart and into effective position by suitable means, such as spring 70 interposed between them. The end portions 71 of the two arms of the fork are cut back, as clearly shown in Fig. 6, so that, in conjunction with the end portions of fingers 69, they form pockets or recesses in which slugs are loosely received, the outward movement of fingers 69 being limited by their lateral engagement with the adjacent faces of the arms of the fork. The circumferential spacing of said slug receiving pockets conforms to the spacing of adjacent slug delivering bushings 63 and tubes 52. A transfer device is shown in Fig. 2 and at the left of Fig. 6 in slug-receiving position, and at the right of Fig. 6 in slug-delivering position. Said device being in the latter position, the swaging punches descend to the position shown in Fig. 2, moving the slug downward into the swaging die and, in cooperation with the swaging stem 57, performing the swaging operation. The die is, of course, provided with the usual vent (not shown) for permitting extrusion of the excess metal.

It is noted in passing that the timing of cam 61 is such that each swaging stem 57 is elevated into engagement with a slug in the transfer fingers before said slug is moved by the descent of the swaging punch 53, and that, during a substantial part of the movement of the slug into the die, stem 57 and punch 53 move in unison, thus positively controlling the movement of the slug. Downward movement of each stem 57 is concluded when the lower end of its holder 58 comes into engagement with set screw 62, and downward movement of the associated punch 53 continues thereafter to perform the swaging operation.

Each slug or workpiece, swaged to a configuration determined by the contour of the die, punch and stem, is ejected from the die by the upward movement in unison of stem 57 and punch 53; and is received in a suitable receptacle carried by a conveyor chain comprising links 75 which engage the teeth of sprocket 55 as heretofore indicated and as illustrated in the aforementioned patent to Johnson. The sprocket chain transverses and forms a connection between several units, each having a different function with respect to the work. One such function is the removal from the conveyor chain receptacles (to be presently described) of the swaged bullets which are inserted in such receptacles in the bullet swaging unit which is the subject of the present invention; other units are not described since they are not part of the present invention. It is sufficient to say that the chain is driven from any suitable source of power applied to the chain at any convenient point. It may, for example, be driven by sprocket 55, power being supplied to any convenient part of the turret. Since the chain em-

braces several units, it traverses a part only of sprocket 55, approaching and receding from this part of sprocket 55 tangentially. Certain mechanisms to be described operate in timed relation to the approach of the chain and its succession of work-holders to successive sectors of sprocket 55 and the turret which rotates therewith.

A preferred form of chain and workpiece receptacle is shown in Figs. 8 and 9. The chain comprises conventional links 75 and pivot pins 16. At appropriate intervals, there are secured to the chain, to extend laterally from its lower portion, workpiece holders 77 comprising workpiece receiving receptacles 78. The portion of each holder 77 forming the lateral open receptacle 78 is preferably of a resilient material, such as rubber or neoprene. The inclination of the opening into the receptacle 78 is such that as the chain approaches the turret the mouth of the receptacle snaps over and embraces a lowered swaging punch 53. The parts being in this relationship, the formed bullet or other workpiece is ejected upwardly from the die and into the receptacle 78, in which it remains, as illustrated in Fig. 7; the swaging punch and stem being thereafter retired, and the workpiece being carried away from the turret in the conveyor chain as the chain recedes from the turret.

A modified form of workpiece receptacle for the chain is illustrated in Fig. 9. As here shown, the receptacle comprises a strap or band 80 of spring metal, which encircles extensions of two adjacent chain pivots 16. Said spring metal band terminates, as shown, in a workpiece receiving pocket 81 having an open mouth adjacent which the end portions of the metal are outwardly turned, as shown at 82, to facilitate snapping over a swaging punch 53.

The operation of the machine may be summarized as follows:

The bullet slugs to be swaged are introduced into the hopper 13. Due to the relative movement of the turret piece 37 in the bottom of the V formed by surfaces 14 and 15, said bullets are sufficiently agitated to drop endwise into the passages 38, forming a column therein. Once during each revolution of the turret, the escape-pawls 42 and 43 are shifted from the Fig. 5 position to the Fig. 1 position and back again to the Fig. 5 position, thus permitting one slug to escape from each passage 38 into the associated delivery tube 52, through which it falls to the transfer device beneath the sprocket wheel 55. At the time of such slug delivery, the transfer devices are in the position shown in Fig. 2, and each slug drops into a transfer device receptacle formed by fork end 71 and associated finger 69; but, should the transfer device be displaced, the slug merely comes to rest upon the upper surface of the fork and awaits the return of the fork to slug-receiving position. Each transfer device in turn, being in a position in which the portion of sprocket 55 on the same radius is not engaged by the conveyor chain, is advanced through the engagement of its cam roller 66 with cam 67 to bring the slugs held therein into alignment with the swaging die and, the slugs being held in this position, swaging punch 53 and swaging stem 57 are actuated to first transfer the slug into the die 56 and then swage it. At this point, the transfer device is retracted to its Fig. 2 position, the spring 70 being compressed as the fingers 69 are displaced to pass the diameter of the swaging punch. Thereafter, each transfer punch is embraced by a workpiece holder 77 on the conveyor chain and,

while in this position, swaging punch and swaging stem are again actuated to move the swaged workpiece into holder 77, after which the stem and punch are retracted, to permit the workpiece to be carried away by the chain.

The particular structures and parts above described are, of course, susceptible to modification and variation.

What is claimed is:

- 10 1. In a machine for the swaging and delivery of bullets into receptacles in a conveyor chain, a continuously revolving vertically disposed turret, a stationary hopper comprising an annular opening concentric with said turret, swaging tool holders mounted for vertical reciprocation in said turret, means for moving said tool holders upwardly comprising a fixed cam, and means for moving said tool holders downwardly comprising a plate mounted for revolution on an inclined axis.
- 15 2. In a machine for mechanical processing of workpieces, a workpiece conveyor, a turret rotatable by said conveyor, a plurality of tool holders reciprocably mounted in said turret, tool holder retracting means comprising a fixed cam, and tool holder advancing means comprising a plate mounted for rotation on an axis inclined to the axis of said turret.
- 20 3. In a machine for mechanical processing of workpieces, a workpiece conveyor, a turret rotatable by said conveyor, a plurality of tool holders each comprising a ball receiving socket reciprocably mounted in said turret, tool holder retracting means comprising a fixed cam, and tool holder advancing means comprising a plate mounted for rotation on an axis inclined to the axis of said turret.
- 25 4. Apparatus for withdrawing workpieces from a mass and delivering such workpieces in an ordered sequence comprising a fixed hopper bowl having an inwardly and downwardly sloping frusto conical wall, a fixed hopper base having an outwardly and downwardly sloping wall, the lower margins of said walls defining an annular opening, a movable member extending into and substantially closing said opening, and a plurality of workpiece receiving passages in said moving member.
- 30 5. Apparatus according to claim 4 in which a plurality of workpiece receiving tubular members are associated respectively with said passages.
- 35 6. Apparatus for withdrawing workpieces from a mass and delivering such workpieces in an ordered sequence comprising a fixed workpiece holder hopper having walls defining an annular opening, a continuously moving turret comprising a member extending into and substantially closing said opening, a plurality of workpiece receiving passages in said member, and a plurality of workpiece transfer devices associated with said passages.
- 40 7. Apparatus for delivering an ordered arrangement of workpieces from a mass of such pieces and performing an operation thereon comprising a vertically disposed fixed hopper provided with a conical bottom and adapted to hold a mass of workpieces, a continuously moving workpiece receiving member at the periphery of said conical hopper bottom having therein a plurality of passages each adapted to receive workpieces from said hopper, an inclined boss associated with said hopper forming a bearing support, a tool actuating member mounted for rotation on said in-
- 45
- 50
- 55
- 60
- 65
- 70
- 75

clined bearing support, a plurality of tools associated respectively with said workpiece passages and actuated by said tool actuating member, and means for aligning workpieces withdrawn from said passages with said tools.

8. Apparatus according to claim 7 in which the hopper bottom is provided with a planar downwardly facing surface perpendicular to the axis of said inclined boss and engaged by devices associated with said tool actuating member.

9. Apparatus according to claim 7 in which said tool actuating member is provided with a plurality of substantially hemispherical sockets each adapted to receive a ball member associated with an actuated tool.

10. Apparatus according to claim 9 in which said tools are supported with the ball members in bearing engagement in said sockets by the engagement of rollers associated with said tools with a fixed track in spaced and parallel relation to the downwardly facing surface on said hopper.

11. Apparatus according to claim 10 in which the tools are arranged in groups, the tools of each group being joined by a crosshead, each crosshead comprising a ball receiving recess and having associated therewith a roller engaging said track.

12. Apparatus for the swaging of bullets comprising a continuously revolving turret, a conveyor or in operative engagement with said turret, individual bullet receptacles on said conveyor, a slug-containing member on said turret, a swaging die on said turret, means for transferring workpieces one at a time from said containing member to said die, means on said turret for swaging a slug in said die into a bullet, and means for ejecting the swaged bullet from said die into a receptacle on said conveyor. 35

13. Apparatus according to claim 12 in which the swaging means comprises a lower reciprocable supporting and ejecting stem and an upper reciprocable feeding and swaging punch. 40

14. Apparatus according to claim 13 in which the transfer means moves a slug from alignment with the slug-containing member into alignment with said feeding and swaging punch, which punch thereafter reciprocates to remove a slug from said transfer means into said die.

15. Apparatus according to claim 14 in which the slug is removed by said punch while said transfer means is in advanced position and said transfer means is retracted while the punch is in its advanced position.

16. Apparatus according to claim 15 in which the bullet receptacles on the conveyor come into bullet-receiving position while said punch is advanced and in so doing embrace the shank of said punch.

17. Apparatus according to claim 15 in which the bullet receptacles on said conveyor are spring fingers adapted to spread and embrace the shank of said punch while said punch is in its lowered bullet swaging position.

18. Apparatus according to claim 15 in which the supporting and ejecting stem and the swaging punch are lifted in unison to deliver a swaged bullet to a conveyor receptacle and thereafter retired to clear the bullet in said receptacle.
